STEAM BOARD

Filed Jan. 29, 1927

Inventor:

Herman Betke.

By Silas S. Sweet.
Attorney.

UNITED STATES PATENT OFFICE.

HERMAN BETKE, OF DENVER, COLORADO.

STEAM BOARD.

Application filed January 29, 1927. Serial No. 164,471.

This invention relates to apparatus of a class commonly known as steam boards adapted for use in removing wrinkles from or raising the nap of fabrics by the passage of steam therethrough, and more particularly to a specific construction of steam board adapted for use in steaming sleeves and other tubular portions of garments and commonly known as a steam sleeve board; 10 an object of the invention being to provide a steam board having an independent, internal heating element whereby a high initial temperature of the apparatus is established and maintained and the possibility of 15 water of condensation forming through contact of steam with cold metal parts of the apparatus is minimized.

A further object of the invention is to be found in the provision of automatic means 20 whereby water of condensation may be trapped within and removed from said apparatus without interrupting the operating efficiency thereof.

A further object of the invention is to provide a construction of internal heating element for steam boards which is simple, positive and efficient in operation.

A further object of the invention is to provide means for use in combination with my 30 improved steam sleeve board whereby trimmings, such as fur and the like, that might be damaged in the steaming process, may be protected during the steaming operation without being removed from the garment to 35 be treated.

A further object of the invention is to provide a simplified system of connections between my improved steam board and a source of steam, wherein the number of control 40 means to be actuated by the operator is reduced and the operation of the board correspondingly simplified.

My invention consists in the construction, arrangement and combination of elements 45 hereinafter set forth, pointed out in my claims and illustrated by the accompanying drawing, in which—

Figure 1 is a side elevation of one form of my improved apparatus assembled in position for use, dotted lines indicating the position of the trimming protecting device or shield when the latter is employed. Figure 2 is a vertical longitudinal section of the apparatus shown in Figure 1, a portion only 50 of the supporting standard being shown.

Figure 3 is a vertical transverse section on the indicated line 3—3 of Figure 1, the greater portion of the supporting standard being omitted. Figure 4 is a plan of a modified form of my apparatus, steam connections thereto being merely indicated and control means omitted. Figure 5 is a vertical longitudinal section of the form of apparatus shown in Figure 4, the major portion of the supporting standard being omitted. 60 Figure 6 is a vertical transverse section on the indicated line 6—6 of Figure 4, a portion only of the supporting standard being shown. Figure 7 is an isometric view of the trimming protecting device or shield adapted for use with my apparatus. 65

In the construction of my improved apparatus, as shown in Figures 1, 2 and 3, an elbow is formed, preferably by casting or molding, comprising cylinders 10 and 11, of 70 different diameters, axially intersecting one another at substantially right angles. The cylinder 11 is shown as of lesser diameter than the cylinder 10 and is formed with an axial bore 12 intersecting a bore 13 of 75 greater diameter formed in the cylinder 10 and opening to one end thereof. The open end of the bore 12 is internally threaded and is adapted to be screwed on and thereby secured to the closed upper end of a tubular standard 14, the lower end of said standard being provided with a base member 15 whereby the apparatus may be fastened to a floor, bench or the like. The closed end of the cylinder 10 is relatively 80 thick and is provided with an internally-threaded recess concentric with the bore 13 and opening thereto, said recess being 85 adapted for engagement with the threaded end of a cylinder 16 which is thereby supported laterally of and at substantially right angles with the standard 14. The cylinder 16 is preferably formed of rust resisting 90 sheet metal such as copper, brass, aluminum or the like, is of less diameter than the bore 100 13 and is formed with an open end adapted to be received in the recess and a closed opposite end, said closed end having any desired shape, the semi-spherical form illustrated being preferable. A second cylinder 17, having one open and one closed 105 end and external threads adjacent said open end, is formed of rust resisting material and with a diameter greater than that of the cylinder 16 and is adapted for engagement 110

with threads formed internally of the bore 13 adjacent the open end thereof, whereby the cylinder 17 is supported by and laterally of the elbow in concentric relation with and 5 spaced from the cylinder 16. A steam line 18 leads from any suitable source of steam such as a boiler (not shown) to and through the end closure of the cylinder 10 and an extension of said line, 19, extends longitudinally 10 within the cylinder 16 to a point adjacent the closed end thereof, where it terminates in an open end. A return pipe or line 20 is likewise tapped through the end closure of the cylinder 10 and communicates 15 with the chamber within the cylinder 16 at its lowermost point, leading from thence to the boiler or source of steam. Cut-off valves or other control means may be installed in the lines 18 and 20 when and as desired, 20 but such valves are not to be employed in the operation of the apparatus, it being desirable that steam shall at all times be led through the pipe 18 and extension 19 into the chamber within the cylinder 16, circulated 25 within said chamber and, together with the water of condensation that may form, returned to the boiler by means of the pipe 20. Thus is provision made for establishing and maintaining, automatically, 30 a high temperature within the apparatus to the end that all operating parts of the apparatus may be heated and so that operating steam admitted to the apparatus will not be subjected to cooling and condensation 35 through contact with cold metallic parts. A branch 21 diverges from the steam line 18 and leads through a control valve 22 to a passage 23 communicating through the end closure of the cylinder 10 with that 40 portion of the bore 13 surrounding the cylinder 16. The valve 22 is normally closed and is preferably equipped with quick-acting means for manual operation, said operating means preferably including a handle 45 of heat insulating or non-conducting material, as indicated at 24. The upper surface of the cylinder 17 is provided with a plurality of closely spaced, minute perforations, indicated at 25, through which steam 50 admitted to the space between the cylinders 16 and 17 may escape and act in and upon garments and fabric spread over said surface. The cylinder 17 should be slightly inclined with the horizontal to the end that 55 water of condensation collecting within said cylinder may drain to the elbow and be trapped within the chamber formed by the bore 12 and closed end of the standard 14, from whence a drain pipe 26 leads through 60 a trap 27 to a receptacle, sewer connection or the like. The trap 27 may be of any desired style, a simple conventional form consisting of a recurved pipe being shown, it being the function of said trap to prevent 65 easy escape of the steam within the cylinder

17 and compel said steam to circulate within said cylinder and through the perforations 25.

The modifications illustrated in Figures 4, 5 and 6 are purely matters of structure and form, the principles of operation being in all respects the same as above set forth. In the latter views, the cylinders 16 and 17 are shown tapered in width and thickness, whereby a greater range of usefulness of the apparatus may be had. The cylinder 17 is shown with an annular flange 17' about its open end in place of the threads above described, said flange being adapted to be clamped to the open end of the cylinder 10 by means of a collar 28 and cap screws 29; a gasket 30 being interposed between said flange and the end of the cylinder 10 to prevent leakage of steam. It is of course apparent that this latter method of connecting the cylinders 10 and 17 may readily be substituted for the threaded relation in the form shown in Figures 1 and 2. In Figures 4, 5 and 6 the cylinder 11 is shown with a closed outer end provided with an annular flange 11' adapted to be bolted to a corresponding flange 14'' formed on the upper end of a standard 14', said standard being illustrated as having a cruciform cross section. These modifications are but variations of the construction hereinbefore described and are adaptable to the form of apparatus shown in Figures 1 and 2.

Inasmuch as garment trimming, such as fur and the like, may be damaged through contact with steam and heat, a protecting shield adapted to slip over the cylinder 17 and insulate portions of the garment from said cylinder, is provided. As shown in Figure 7, such a shield may consist of a sheet of fiber or similar material, 31, to one surface of which is secured by shellac or glue and stitching a sheet of felt or similar absorbent material, 32, the composite sheet thus formed being rolled to form a cylinder 110 of suitable diameter with the absorbent material on the inside, the edges of the sheet being overlapped and secured by rivets 33 or other fastening means. When the shield as above described is in use on the apparatus, 115 the absorbent material serves to insulate the fiber 31 from the heat of the steam and absorbs the moisture therefrom, so that portions of the garment in contact with said shield are protected from all contact with 120 said steam.

The operation of the apparatus is quite simple. Steam circulating through the line 18, extension 19, chamber of the cylinder 16 and line 20 maintains the apparatus at 125 high temperatures and ready for use. A garment or fabric being spread over the perforated surface of the cylinder 17 and the valve 22 being opened, steam is admitted from the line 18 through the branch 21, 130

valve 22 and passage 23 to the chamber between the cylinders 16 and 17, from whence, owing to the resistance of the trap 27, it is forced through the apertures 25 and the fabric thereover. Water of condensation and excess steam is exhausted from the cylinder 17 through the drain 26 and trap 27 and water forming within the cylinder 16 is returned to the boiler with the steam 10 through the pipe 20, thus insuring that the steam emitted through the perforations 25 is at all times dry and of high temperature.

I claim as my invention—

1. A steam board comprising a suitable support, an elbow member carried by said support, spaced, parallel, concentric cylinders having closed outer ends carried by and projecting laterally of said elbow, the outer of said cylinders being perforated and the inner of said cylinders being imperforate and sealed from the outer cylinder, and means whereby steam may be circulated continuously within said inner cylinder and selectively within said outer cylinder.
2. A steam board comprising a suitable support, an elbow member carried by said support, a perforated cylinder having a closed outer end carried by and projecting laterally from said elbow, a bore within 30 said elbow communicating with a chamber within said cylinder and also communicating with a chamber within the vertical leg of said elbow, a trapped drain leading from said last named chamber, a heating element within and sealed from the chamber within said cylinder, means for circulating steam within said heating element and manually controlled means for circulating steam within said cylinder.
3. A steam board comprising a suitable support, an elbow member carried by said support, a laterally-projecting perforated, hollow member closed at its outer end and communicating with a bore within said elbow and carried thereby, a chamber having a trapped outlet formed in the vertical leg of said elbow and communicating with said bore, a heating element within said hollow member and means whereby steam may be circulated continuously through said heating element and selectively through said hollow member.
4. A steam board comprising a suitable support, a steaming element and a heating element within said steaming element, said steaming element comprising a laterally-projecting hollow member closed at its outer end, vented on its upper surface and supported by and opening into an elbow carried by 60 said support, a chamber in said elbow below and communicating with said hollow

member, a trapped drain communicating with said chamber and manually-operable steam control means communicating with said hollow member whereby steam may be circulated therethrough.

5. A steam board comprising a suitable support, a steaming element, means whereby steam may be circulated through said steaming element, and a heating element 70 within said steaming element, said heating element comprising a hollow member within and sealed from said steaming element, a steam line intersecting one end of said hollow member, longitudinally traversing said 75 member and opening adjacent the opposite end thereof and a return pipe opening through said intersected end adjacent the lowermost plane of said member, together with means whereby steam may be circulated 80 through said line, hollow member and pipe.

6. In an apparatus of the character described, a support, a steaming element comprising a perforate tubular member extending laterally from said support, means 85 whereby steam may be circulated through said steaming element, a heating element adapted for continuous circulation of steam therethrough and comprising a tubular element within and sealed from said steaming 90 element, a steam line connected with one end of said tubular element, an extension of said line within said element and opening adjacent the end thereof removed from said intersected end and combined draining and 95 steam return means opening through said intersected end adjacent the lowermost plane of said tubular element.

7. In an apparatus of the character described having a standard adapted to be 100 secured to a base and an elbow member supported thereby, a substantially cylindrical head secured at one end to the horizontal arm of said elbow, said head comprising spaced, concentric cylinders, the inner of 105 said cylinders being imperforate and provided with an inlet and an outlet whereby steam may be circulated therein, the outer of said cylinders being formed with vents in its upper convex surface and provided with 110 an inlet whereby steam may be circulated in the space between the cylinders and through said vents and further provided with an outlet communicating to and through said elbow, together with means for conducting 115 and controlling the flow of steam to and through said cylinders.

Signed at Denver, in the county of Denver and State of Colorado, this 22nd day of January, 1927.

HERMAN BETKE.
